L. KAHN

COMBINATION GARMENT

Filed May 22 1923

UNITED STATES PATENT OFFICE.

LEON KAHN, OF BROOKLYN, NEW YORK.

COMBINATION GARMENT.

Application filed May 22, 1923. Serial No. 640,664.

To all whom it may concern:

Be it known that I, LEON KAHN, a citizen of the United States, and resident of the city of New York, borough of Brooklyn, in 5 the county of Kings and State of New York, have invented certain new and useful Improvements in Combination Garments, of which the following is a specification.

This invention relates to women's combination garments, and it has for its object to provide a single article of apparel which efficiently fulfills the three fold requirements of drawers or bloomers, a brassière or body portion and a hip supporter, and which article is light, shapely and comfortable and tends to impart a graceful contour to the figure of the wearer.

A preferred form of embodiment of the invention is illustrated in the drawings, 20 wherein—

Figure 1 is a rear view of the garment in open position, parts of the casings being removed to expose the confined elastics.

Fig. 2 illustrates the garment as in use.

Referring to the drawings, 5 designates a main portion shaped to constitute a bifurcated garment, such as bloomers whereof the leg openings are provided with puckered casings 6 for the reception of elastics 7. The 25 back portion of the bloomers includes a flap 8 which, when the garment is worn, extends from a plane below the hips to the waist line and is provided with a puckered casing 9 for an elastic 10. Secured to the respective ends of the casing are tapes or tie strings 11 adapted to be drawn forwardly and reversely in front of the wearer and tied.

The material constituting the bloomers 40 comprises a middle front portion 12, two lateral panels 13, and a back portion 14 with its flap 8, which portions are sewed together on approximately vertical lines. The parts 12 and 13 extend upwardly to produce the 45 front or bust portion 15 of the brassière or body portion; it being noted that the front of the bloomers extends from the center of the body at one side to the center of the body at the other side, or substantially so; that 50 the back flap is substantially the same width as the front where they join the body, and that the top of such flap is secured about the waist of the wearer by means independently 55 of the body of the garment. The panels 13 are provided with side wings 16 which ex-

tend some distance below the waist line of the garment. The outer edges of these wings are appropriately shaped and are provided with complementary hooks and eyes 17, 18, respectively, or other suitable fasteners. The wings 16 and the adjacent body panels 13 are sewed edge to edge, as at 19, from the top of the garment to a point just above the waist line, and are thence connected by interposed elastic gussets 20 the edges 60 of each of which diverge to a plane below the hips. The wings 16 are provided adjacent the respective gussets with depending extensions 21 having elastic stocking supporters 22. The top of the garment is provided with suitably-disposed shoulder straps 23.

Assuming the garment to be placed as in Fig. 1 of the drawings, the user steps into the bloomers with the back flap hanging 75 down. She then puts her arms through the shoulder straps and pulls the straps up on her shoulders so as to position the brassière or body portion. She then pulls up the back flap, draws the tapes 11 forwardly and 80 reversely around her waist (beneath the body portion) against the action of the elastic 10, and ties together the ends of the tapes. She then pulls the wings 16 backward against the resilient action of the gussets 20 and 85 fastens the meeting edges of the wings along the middle of her back by means of the hooks and eyes. This done, the stocking supporters hang in position for use, and when they are attached to the stockings they 90 exert a resilient downward stress on the body portion. The front of such portion being a continuation of the front of the bloomers, serves to impart a "straight front" to the wearer, and the gussets, snugly 95 embracing the hips and waist, serve not only as a resilient hip support but they also lend a trimness to the figure of the wearer.

From the foregoing it will be seen that my invention provides a single garment 100 combining drawers or bloomers, a brassière or body portion and a hip supporter, which garment is light and comfortable and may be used with or without other underwear, as desired. It may also be worn without 105 outer garments and thus used for bathing and other purposes.

Various changes may be made in the form and construction of the garment without departing from the principle and scope 110

of my invention as defined in the appended claims.

I claim—

1. A combination garment comprising a body portion and bloomers connected thereto, the front of the bloomers being connected to the front portion of the body and extending from the center of the body at one side to the center of the body at the other side, the back of the bloomers being extended to form a flap which extends upwardly to the waist line of the wearer and substantially the same width as the front where they are joined to the body, means for securing the top of the flap about the waist of the wearer independently of the body of the garment, the back of the body being formed of lateral extensions connected to the body portion and arranged to extend over the hips of the wearer, and means for securing the edges of the extensions to each other at the back.
2. A combination garment comprising a body portion and bloomers connected there-

to, the front of the bloomers being connected to the front portion of the body and extending from the center of the body at one side to the center of the body at the other side, the back of the bloomers being extended to form a flap which extends upwardly to the waist line of the wearer and substantially the same width as the front where they are joined to the body, means for securing the top of the flap about the waist of the wearer independently of the body of the garment, the back of the body being formed of lateral extensions connected to the body portion and arranged to extend over the hips of the wearer, there being an elastic gusset in each of the extensions arranged to overlie the hips of the wearer, and means for securing the edges of the extensions to each other at the back.

Signed at New York, in the county and State of New York this 18th day of May, A. D. 1923.

LEON KAHN.
